UNITED STATES PATENT OFFICE.

CLAUD H. E. SCHENCK, OF CLEVELAND, OHIO.

WHEEL-FENDER.

SPECIFICATION forming part of Letters Patent No. 741,171, dated October 13, 1903.

Application filed July 29, 1903. Serial No. 167,439. (No model.)

To all whom it may concern:

Be it known that I, CLAUD H. E. SCHENCK, a citizen of the United States, residing at Cleveland, in the county of Cuyahoga and State of Ohio, have invented new and useful Improvements in Wheel-Fenders, of which the following is a specification.

This invention relates particularly to wheel-fenders adapted to receive and carry the body or obstacle struck; and the object of the invention is to produce an improved construction in which the said body will be inclosed and held on the fender by hinged fender-sections which will act by the weight of the body to inclose the same on the fender.

Further improvements of construction will be apparent in the detailed description following.

In the accompanying drawings, Figure 1 is a side elevation of the fender. Figs. 2 and 3 are details in elevation, showing the means for releasing the front fender-section to permit it to lift, so that a body cannot roll off the main fender. Figs. 4 and 5 are details in elevation of a jointed rod controlling the position of the main fender. Fig. 6 is a detail of the guide-bracket through which the rear arm of the main fender works, and Fig. 7 is a detail in section of the front bar of the fender.

Referring specifically to the drawings, the supporting-frame for the fender is indicated at 6. This is semicircular in shape, and there is a similar frame at each side of the fender. Each frame has a rearwardly-extending arm 7, which is pivoted at 8 to a bracket 9, fastened to the bottom of the car-frame 10, and the rear end of the arm works in a slot in a guide-bracket 11, so that the frames and the fender carried thereby will drop when desired. Normally the fender-frames are held in raised position by a rod 12, having a knuckle-joint at 13. This rod is fastened at its upper end to the car-frame 10 and at its lower end to the arm 7. The joint may be flexed by means of a rope 14, which extends up through the car-floor and into the vestibule of the car in position to be pulled by the motorman. When the rod is pulled, the joint is flexed and the fender will drop to the track. The main fender is indicated at 15, substantially semicircular in shape. At the upper

and lower ends of the frame 3 are pivoted the covering or inclosing fenders 16 and 17. These are normally in the position shown in full lines in Fig. 1 and will respectively drop and lift to take the position shown in dotted lines in said figure when the fender receives a body. This movement is controlled and effected by means now to be described.

The fender 16 is pivoted at 16^a to the upper end of the frame 6, and the pivot-bar carries a sprocket-wheel geared by chain 18 to one of double sprockets 19, supported on a bracket secured to the main frame, and the other sprocket 19 is geared by a chain 20 to a sprocket 21, also supported by a bracket on the frame. The chain 20 carries blocks 22, which are adapted to stop against a bell-crank latch 23, pivoted at 24 to the frame. The other arm of the bell-crank is attached to a rod 25, fixed to the main fender 15. A spring 26 is secured at one end to the arm 7 and is connected by a cord 27 to the chain 20, and the spring tends to pull the chain so as to rotate the sprockets mentioned, and the turn of the sprocket 16^a will drop the fender 16 to the position shown in dotted lines in Fig. 6. When a body is struck and falls into the fender 15, its weight turns the bell-crank and releases the latch, and the spring immediately pulls the chain, so that the inclosing fender drops and meets the lower fender 17, which is lifted, as hereinafter described.

The lower fender 17 is pivoted at 17^a to the lower end of the main frame 6, and the pivot-bar carries a sprocket-wheel, which is geared by a chain 28 to one of double sprockets at 29, the other of which is connected by a chain 30 to a sprocket 31. Said sprockets are carried by suitable brackets fixed to the main frame. At 32 a spring is indicated, connected at one end to the main frame and at the other end by a cord 33 to the chain 30. This spring tends to pull the chain and rotate the sprockets, causing the lift of the front fender 17 to the position shown in dotted lines in Fig. 1. This movement is prevented by a latch controlled by the motorman. This latch consists of detents 34, pivoted to the front end of a bar 35, which slides in a block 36, secured to the frame 6. The rear end of the bar is joined to a toggle 37, the movement of which is controlled by a rope 38, which extends over suit-

able guide-pulleys to the car-vestibule in position to be pulled by the motorman. When the toggle is flexed, as it is normally, the detents 34 project into the links of the chain 30 5 and prevent any movement thereof. After a body shall have been struck the motorman pulls the chain 38, which straightens the toggle and withdraws the detents from the chain. This permits the spring 32 to act and lift the 10 fore fender 17 by the means described.

The front bar of the fore fender 17 is of peculiar and improved construction. It consists of a rubber tube 39, receiving therein 15 end pieces 40, which are connected by a spring 41 inside the tube. These end pieces are supported at the lower or front ends of the frames 6. When a body is struck, the rubber and elastic bar will yield, so that no injury will be produced by the impact.

20 At the front end of the frame 6 rollers 42 are journaled. When the knuckle-bars 12 are flexed and the frames turn on the pivot 8, the rollers drop to and ride along the track. As said before, the rod 14 is pulled and the 25 knuckle-bars flexed at the first sign of danger.

The fenders are suitably constructed of slats or other material.

It will be seen that when a body is received 30 on the fender 15 the fenders 16 and 17 close and meet to hold the body on the fender.

What I claim as new, and desire to secure by Letters Patent, is—

1. The combination with a main curved fender, of inclosing fenders hinged to the upper and lower ends thereof and means to close 35 said fenders, to retain a body on the main fender, substantially as described.

2. The combination with a main fender, of an inclosing fender hinged to the top thereof, and means actuated by the weight of a body 40 on the main fender to drop the inclosing fender, substantially as described.

3. The combination with a fender having a rearwardly-extending arm pivoted to the car-body, of a jointed rod between the arm and 45 the car-body, sustaining when straight the fender in raised position, and a rope connected to the rod, to flex the joint and permit the fender to drop.

4. The combination with a curved main fender, of inclosing fenders hinged to the upper and lower ends thereof, springs having connections to the inclosing fenders and acting to close the same, detents engaging said connections to prevent the action of the springs, 50 and means to release said detents.

In testimony whereof I have signed my name to this specification in the presence of two subscribing witnesses.

CLAUD H. E. SCHENCK.
